HARRY E. SCOTT, OF CLEVELAND HEIGHTS, OHIO, ASSIGNOR TO THE THEW SHOVEL COMPANY, OF LORAIN, OHIO, A CORPORATION OF OHIO

DIPPER STICK AND BOOM STRUCTURE

Application filed May 2, 1929. Serial No. 359,855.

The invention disclosed in this application relates generally to dipper stick and boom structures for use in power shovels, and particularly to the mounting of the stick in the boom.

The object of this invention is to improve the mounting of the dipper stick in the boom whereby the stick is permitted free movement in the boom in spite of its position and the various stresses brought to bear upon it, and thereby to improve the driving operation between the driving element carried by the boom and the stick.

Generally speaking, the boom is divided into two side boom portions with the stick passing between these sides. Mounted between these sides is a suitable driver usually in the form of a pinion which meshes with a rack carried by the boom, the stick being held with its rack in engagement with the driver by a portion through which the stick has sliding engagement, and which forms a guide therefor. In another arrangement, this same general structure is employed except that in place of the guiding and holding means between the stick and the driver, as above specified, the boom is provided with guides having circular tracks concentric with the driver and receiving circumferentially spaced rollers, two in each guide and mounted on roller shafts each of which has other rollers engaging the back of the stick and providing an anti-friction means for holding stick and its rack in engagement with the driver.

The present invention relates specifically to a modified form of anti-friction mounting between the circular guides, carried by the boom sides and stick, whereby the stick throughout its entire range of movement and in spite of its twists, strains and stresses is free to move without transmitting such stresses unduly to the rollers or members engaging in the circular guides. Conversely, the strains and stresses set up by the rollers in the guides are not transmitted to the stick in a manner to interfere with its free movement and operation.

The invention is specifically exemplified in the following description, drawings and claims.

In the drawings Fig. 1 is a plan view partially in section showing the boom, stick and guide assembly; Fig. 2 is a side elevation with parts broken away; and Fig. 3 is a plan view of the anti-friction device or trolley.

In the drawings the boom comprises two side members 1 and 2 spaced apart at a suitable medial point as indicated at 3, for receiving the stick, its drive and its mounting. At the point in the boom where the stick mounting is to be applied, the two side members 1 and 2 are provided with bearings indicated at 4 for receiving a transverse driving shaft 5 provided, between the members, with a driving pinion 6. The shaft 5 is further provided with a driving member or drum 7 adapted to be driven by any suitable means. The pinion 6 is less in width than the space between the side members 1 and 2, and in this space and on each side is the stick guiding means which comprises two opposed and cooperating circular guide members each consisting of a circular back 8, a center hub 9 for receiving the bearings 4, and peripheral side face recesses 10 for receiving the wheels of the trolley as will appear. These two guide members are secured to their respective side boom members 1 and 2, and have, at the rear and toward the lower end of the boom, spacer bosses 11 one on each member, which meet at the center of the boom and serve to properly space the two guide members. Suitable aligning openings are provided through the two guide members in the center of the bosses 11 for receiving a tie rod or bolt 12 holding them in axial alignment.

From the foregoing it will be seen that there are opposed guiding members mounted concentrically about the axis of the driving shaft and its pinion, and secured to the boom sides so that the circular track ways in these guide members are concentric with the driving pinion and its shaft.

Engaging the pinion 6 is a rock 13 carried by the stick 14 which is usually provided with a shovel, excavator or scoop at its lower end.

The foregoing sets forth a structure which

is now familiar to those skilled in the art and does not form any specific part of the invention except in so far as it enters into the combination. A specific embodiment of the mechanism which forms the basis of the invention, will now be described.

In order to hold the stick 14 in engagement with the pinion 6 and to permit it to slide freely throughout its range of movement, 10 a suitable accommodating trolley or anti-friction backing device is provided and it consists of a cross-shaped frame including the transverse tubular member 15 and the longitudinal member 16, these two members crossing at substantially their center. Mounted in the tubular member 15 is a roller shaft 17 carrying at its outer end rollers 18 adapted to engage in the circular track ways 10 of the guiding members. The longitudinal member 16 is provided near both of its ends with transverse slots 19 extending upwardly from the bottom and receiving squared portions 20 of shafts 21 extending out at both sides. Each of the four end extensions thus formed, is provided with a roller 22. Engaging each squared portion 20 at the center is a screw 23 held in any suitable position by a check-nut 24. It is obvious that these adjusting screws when moved downward will engage the squared portions 20 of the shafts and take up any undesirable back lash between the track ways 10 and the stick 14. The center shaft 17 is held in place by a suitable set screw arrangement 25.

35 The four rollers 22 carried by the end shafts engage the back side of the stick and hold the rack 13 in engagement with the driving pinion, while the two rollers 18 bear in the annular recesses 10 for the purpose.

40 It will be seen from the foregoing that the anti-friction trolley arrangement herein described will provide a backing means for the stick and its rack, and will permit free movement of the stick throughout its entire range 45 without the transmission of undue strains and stresses.

Having described my invention, I claim:

1. A trolley of the class described and comprising a cruciform frame, end rollers disposed one on each side of each end of the longitudinal frame member, and side rollers disposed at the ends of the transverse frame member, with portions overlying the end rollers.
- 55 2. In combination with a pair of spaced guides having circular trackways and a dipper stick extending between said guides, a trolley comprising a frame and idler rollers carried thereby, said rollers including a pair of aligned side rollers bearing in said annular trackways, and paired end rollers mounted to move on axes ahead and behind that of said side rollers, and bearing against said dipper stick.

3. In combination with a pair of spaced guides having circular trackways and a dipper stick extending between said guides, a trolley comprising a frame and idler rollers carried thereby, said rollers including a pair of side rollers bearing in said annular trackways, and end rollers mounted to move on axes ahead and behind that of said side rollers and bearing against said dipper stick, and means for adjusting one of said axes in said frame to adjust the said bearing of a corresponding roller and hence to effect adjustment of the said bearings of the other rollers.

4. In combination with a pair of spaced guides having circular trackways and a dipper stick extending between said guides, a trolley comprising a frame and idler rollers carried thereby, said rollers including a pair of side rollers located on a central axis and bearing in said annular trackways, and pairs of end rollers located on axes ahead and behind that of the side rollers and bearing against said dipper stick, and means providing for angular movement of one of said axes in said frame to allow the said bearings of its rollers to have differential relation.

5. In combination with a pair of spaced guides having circular trackways and a dipper stick extending between said guides, a trolley comprising a frame and idler rollers carried thereby, said rollers including a pair of side rollers located on a central axis and bearing in said annular trackways, and pairs of end rollers located on axes ahead and behind that of the side rollers, and bearing against said dipper stick, means for adjusting one of said axes in said frame to adjust bearing of its corresponding rollers, and means providing for angular movement of one of said axes in said frame to allow said bearings of its rollers to have differential relation.

In testimony whereof I hereby affix my signature.

HARRY E. SCOTT. 110
